REVERSING SEAT BASE WITH FORWARD SHIFT

Oiva E. Hill, Gardner, Mass., assignor to Heywood-Wakefield Company, Gardner, Mass., a corporation of Massachusetts

Application October 19, 1939, Serial No. 360,103

6 Claims. (Cl. 155—96)

This invention relates to car-seat bases of the type whereby the seat reverses by rotation and at the same time shifts horizontally to avoid collision with the wall of the vehicle or with adjacent seats. In a vehicle such as a railroad car as it is desirable that the seats be located as close to each other as is consistent with comfort in order to obtain maximum seating capacity for the car. It is also desirable to place the seats as near as possible to the adjacent wall of the vehicle so as to utilize substantially the entire width of the car for seat-width and aisle-width. Many seat-base mechanisms have heretofore been devised for shifting a car seat away from the wall during the initial portion of its reversing movement so that the corner of the seat will clear the wall as it turns.

According to the present invention, the seats are rearwardly offset on their pedestals so that, when alternate seats are reversed and are thus front-to-front or back-to-back, maximum spacing is obtained between opposing front edges of seats which face each other, and minimum spacing is obtained between the seats which are back-to-back. To avoid clashing between the backs of adjacent seats during reversing movement, mechanism is provided by which the seat is given a substantial forward shift during the initial portion of the reversing movement. This separates the backs of adjacent back-to-back seats to permit the seats to turn without interference. It is an object of the invention to provide cam mechanism by which such shifting movement is obtained with a smooth reversing movement which is free from sticking or jerky action.

Other advantageous features will be apparent from the disclosure of the invention in the following description thereof, and from the drawings of which.

Figure 1 is a fragmentary plan view of a vehicle floor showing a number of seats mounted thereon.

Figure 2 is a side elevation of the same.

Figure 3 is a plan view of a member of the seat frame.

Figure 4 is a section on the line 4—4 of Figure 3.

Figure 5 is a plan view of a guide link for a car seat.

Figure 6 is a plan view of a pedestal for a car seat, showing thereon the frame member and guide link illustrated in Figures 3 and 5.

Figure 7 is a sectional view on the line 7—7 of Figure 6.

Figure 8 is a section on the line 8—8 of Figure 7.

Figures 9, 10, 11 and 12 show the same members as are shown in Figure 6, the movable members being in different positions of operation.

Figure 1 is a partial plan view of a vehicle such as a railroad car indicating a portion of the floor 10 and one of the side walls 12. A number of double seats 14 are indicated, some of these seats being in reversed position. As shown in Figure 2, each of these seats may comprise a stationary pedestal 20 on which is mounted a seat frame 22 carrying a cushion 24, the seat frame having side frames 26 carrying arm rests 28, and backs 30 which are preferably adjustable. In order to conserve space within the vehicle, the seats are preferably arranged so that, when two seats are back-to-back, the tops of the backs will be close together as indicated in Figures 1 and 2. It is evident that with seats arranged as shown, some provision must be made to prevent interference between the backs of the seats when one seat is rotated to its other position of use. It is desirable that the seats be capable of rotation without tilting the backs forward as could be done to avoid interference. According to the present invention, the entire seat is caused to shift forward a substantial distance during the initial portion of a turn, the backs of the seat thus avoiding interference with the back of the adjacent seat.

Cam mechanism for effecting forward shifting movement of each seat as it starts to turn and for causing a corresponding rearward movement of the seat during the final portion of the turn is illustrated in Figure 6. As therein shown, the pedestal 20 is provided with a flat top 32 having an aperture 34 therein which is roughly triangular. One of the sides 36 of the triangle is a straight line parallel and adjacent to the front-to-rear median of the seat when the seat is in either position for use. The other two sides 38 and 40 of the triangle are chiefly arcuate in shape. The seat frame 22 is preferably adapted to slide on the plane top 32 of the pedestal and its movements thereon are guided by cam mechanism including a guide link 42 such as is shown in Figures 5, 7 and 8. This guide link is elongated and at the ends thereof are cam followers 44 and 46 which engage the cam edges 36, 38 and 40 and move along these edges during rotative movement of the seat. During the first half of such rotative movement of the link, its center point moves horizontally away from one end of the pedestal and moves back towards said end of the pedestal

during the final half of a rotative movement, in a manner similar to that described and illustrated in Patent No. 2,215,817. In the present invention, the seat carriage, instead of being fixed on the link 42, is movable relatively thereto in a straight line by virtue of a pin and slot connection. The seat carriage partakes of the rotational movements of the link, such movements being modified by cam-controlled horizontal sliding movements of the carriage relative to the link. The cam followers 44 and 46 are coaxial, respectively, with a pair of studs 50 and 52 which project upward from the link 42 and which are slidable in elongated slots 54 and 56 in the frame member 60 shown in Figures 3 and 4. This frame member is preferably a bar or channel piece which is a part of the seat-frame and lies in the front-to-rear or longitudinal median plane thereof, the long axis of the member indicating the direction in which the seat faces at any moment. Since the studs 50 and 52 ride in the slots 54 and 56, respectively, the guide link 42 is maintained at all times parallel to the bar 60, so that as the seat is reversed the rotative movement of the bar 60 is accompanied by similar rotative movement by the link 42. Thus the bar 60 and the link 42 rotate together but are relatively slidable longitudinally, such sliding movement being limited by the length of the slots 54 and 56. Figures 6, 9, 10, 11 and 12 represent successive positions through which the bar 60 and the link 42 pass when the seat is being reversed.

Permanently secured to the bar 60 so as to be a part thereof is a double bracket 62, at the ends of which are a pair of cam followers 64 and 66. These cam followers are below the level of the pedestal top 32 when the seat is assembled and engage cam edges formed on a cam plate 70 which is secured to the pedestal below the top 32, as indicated in Figure 7. The cam edges of the plate 70 are so designed as to control the movements of the seat relative to the guide link 42 during the reversals of the seat. The movement of the seat relative to the pedestal is further modified by the engagement of the cam followers 50 and 52 on the guide link 42 against the edges of the aperture 34.

The action of the two sets of cam edges during the reversing movement of the seat can be observed by comparing the positions of the parts shown in Figures 6, 9, 10, 11 and 12, the progress of rotation of the seat being indicated by the positions of the bar 60. Figure 6 shows the position of the seat-frame bar 60 when the seat is in one of its positions for use, the back of the seat being over the right-hand end of the bar. Reversing movement of the seat is brought about by rotating the seat in a clockwise direction. This causes the cam follower 46 to travel along the arcuate cam edge 38 while the cam follower 44 remains in its corner. At the same time the cam follower 66 rides along a suitably curved cam edge 72, which, as indicated in Figure 9, has the effect of quickly shifting the seat forward as far as the slots 54 and 56 will permit. As the cam follower 66 leaves the edge 72, the cam follower 64 rides onto a cam edge 74 of the plate 70 so as to maintain the seat in its forward position relative to the guide link while the seat is moving through the position illustrated in Figure 10. At this stage, the cam follower 46 on the guide link has reached the corner between the cam edges 38 and 40. At the same time the cam follower 64 is about to ride clear of the cam edge 74 while the cam follower 66 rides onto a corresponding cam edge 76. Thus the seat continues to be main-

tained in its forward position relative to the guide link until the position shown in Figure 11 is reached. At this stage the cam follower 66 is about to ride clear of the cam edge 76 and the cam follower 64 is coming into engagement with a cam edge 78 which corresponds to the cam edge 72. Further rotation to the position shown in Figure 12 results in a rapid rearward movement of the seat relative to the guide link, so that when the seat reaches its reversed position of use, it is in its rearmost position relative to the guide link 42. The cam edges around the aperture 34 and the cam edges on the plate 70 cooperate to shift the seat horizontally during its rotating movements, the cam edges being shaped as shown to avoid abrupt changes in direction or speed of horizontal movement of the center point of the seat during reversal thereof, thus ensuring a smooth, continuous swing of the seat from one position to the other.

Details of the structure of the guide link are illustrated in Figures 7 and 8 which indicate that the link may be substantially hollow or channelled and may be provided with arcuate end pieces 80 and 82 one of which is axially movable with respect to the body of the link, being mounted on a stem 84 which telescopes into an end of the body of the link 42. Inward movement of the stem 84 is against the pressure of a compression spring 86 suitably mounted within the link. The end pieces 80 and 82 fit into arcuate recesses in fixed castings 88 and 90 carried by the side rails of the pedestal so as to maintain the link, and therefore the seat itself, yieldingly in either of its reversed positions. A fixed lug 92 underneath the end piece 80 engages a shoulder 94 on the casting 88 or a similar shoulder 96 on the casting 90 to limit the rotative movement of the seat to a half turn, that is, 180°. Immediately below the cam followers 44 and 46 are circular elements 100 and 102 which project under the top 32 adjacent to the edges of the aperture 34 to serve as hold-down elements maintaining the seat in an upright position on the pedestal.

It is evident that various modifications and changes may be made in the embodiments of the invention herein shown and described without departing from the spirit and scope thereof as defined in the following claims.

I claim:

1. A reversing seat-base mechanism comprising a stationary pedestal including a top with cam edges thereon, a seat frame rotatable on said pedestal 180° from one position for use to the reversed position, and means guiding said seat frame in its reversing movements, said guiding means including an elongated guide link extending in a front-to-rear direction when the seat is in either position for use and slidably connected to said frame for movement relative to said frame in the direction of the long axis only of the link, a pair of cam followers at the ends of said link arranged to move along and be guided by said cam edges during reversing movements of said seat frame, said cam edges being shaped to cause the center point of the link to move away from one end of the pedestal during the initial portion of a reversing movement of the link and seat frame and to move back toward said end of the pedestal during the final portion of said reversing movement, a pair of cam followers mounted on said seat frame, and stationary cam edges engaged by said last-mentioned followers to slide said seat frame on said guide link during the initial and final stages of the reversing movements of the seat frame.

2. A reversing seat-base mechanism comprising a stationary pedestal including a top having an opening therein forming cam edges, a cam plate mounted parallel to said top and formed with cam edges, a seat frame rotatable on said top 180° from one position of use to the reversed position, a guide link between said pedestal and seat frame to modify the reversing movements of said seat frame, means on said link and frame preventing relative movements thereof other than in the direction of the long axis of the link, a pair of cam followers on said link engaging the cam edges on said top, and a pair of cam followers on said frame engaging the cam edge on said plate to control the shifting movement of the seat frame relative to said link during reversing movements of the frame and link.

3. A reversing seat-base mechanism comprising a stationary pedestal having an approximately triangular aperture in the top thereof forming cam edges, a reversible seat frame on said pedestal having a pair of aligned slots on the longitudinal median thereof, a guide link having upstanding studs at its ends slidable in said slots respectively, a pair of cam followers at the ends of said link normally located in two corners of said aperture but movable along the edges thereof during reversing movements, a pair of cam followers secured to said frame, and stationary cam means engaged by said last-named followers to cause the frame to slide on said link during the initial and final stages of the reversing movements of the seat frame.

4. A reversing seat-base mechanism comprising a stationary pedestal having an aperture in the top thereof forming cam edges, a seat frame movable on said pedestal to reverse its position thereon, a link between said pedestal and said frame upon which the frame is carried during the reversing movements of the frame, said frame including a bar extending along the longitudinal median of the frame and provided with a pair of elongated aligned slots, a pair of studs on said link extending through said slots respectively and slidable therein whereby said link is maintained in the longitudinal median plane of the frame, a cam follower at each end of said link engaging said cam edges to guide the movements of said

link during reversing movements of the seat, a pair of cam followers carried by said bar, and stationary cam means engaged by said last-mentioned cam followers to cause said frame to slide on said guide link during the initial and final stages of the reversing movements of the frame.

5. A reversing seat-base mechanism comprising a stationary pedestal having an aperture in the top thereof forming cam edges, a seat frame movable on said pedestal to reverse its position thereon, a link between said pedestal and said frame upon which the frame is carried during the reversing movements of the frame, said frame including a bar extending along the longitudinal median of the frame and provided with a pair of elongated aligned slots, a pair of studs on said link extending through said slots respectively and slidable therein whereby said link is maintained in the longitudinal median plane of the frame, a cam follower at each end of said link engaging said cam edges to guide the movements of said link during reversing movements of the seat, a stationary cam plate mounted within said pedestal below the top thereof, a transverse bracket secured to said bar and extending down through the aperture in the pedestal top, and a pair of cam followers carried by said bracket and engaging said cam plate to cause the frame to slide on the link during the initial and final stages of the reversing movements of the seat.

6. A reversing seat-base mechanism comprising a stationary pedestal, a seat frame rotatable on said pedestal 180° from one position for use to the reversed position and horizontally movable during rotation, and means for controlling the horizontal movements of said frame during rotation, said means including a guide link member connecting said frame to said pedestal and rotatable with said frame 180°, cam means on said pedestal and guide link controlling movements of said guide link relative to said pedestal, means limiting the movements of said frame relative to said guide link to a straight line, and cam means on said pedestal and frame controlling the movements of said frame relative to said guide link during rotation of said guide link and frame.

OIVA E. HILL.
